UNITED STATES PATENT OFFICE

105,116

DESIGN FOR A COMBINED TOOTH AND GUM MASSAGER OR LIKE ARTICLE

Edna Opal Love and Emmett J. Molitor, Portland, Oreg., assignors to Lomo Gum Massager Co., Portland, Oreg., a corporation of Oregon

Application May 20, 1936, Serial No. 62,746

Term of patent 14 years

To all whom it may concern:

Be it known that we, Edna Opal Love and Emmett J. Molitor, both citizens of the United States, residing at Portland, in the county of Multnomah and the State of Oregon, have invented a new, original, and ornamental Design for a Combined Tooth and Gum Massager or Like Article, of which the following is a specification, reference being had to the accompanying drawing, forming part thereof.

Fig. 1 is a perspective view of a combined tooth and gum massager or like article, showing our new design.

Fig. 2 is a top plan view thereof.

Fig. 3 is a side end view; and

Fig. 4 is a front end view thereof.

We claim:

The ornamental design for a combined tooth and gum massager or like article, as shown.

EDNA OPAL LOVE.
EMMETT J. MOLITOR.
